UNITED STATES PATENT OFFICE.

FRANK LAW, OF OAKVILLE, ONTARIO, CANADA.

DESIGN FOR A TIRE.

Application filed July 6, 1923. Serial No. 6,712. Term of patent 7 years.

To all whom it may concern:

Be it known that I, FRANK LAW, a citizen of the Dominion of Canada, and resident of Oakville, county of Halton, Province of Ontario, Canada, have invented a new, original, and ornamental Design for Tire, of which the following is a specification.

In the accompanying drawing:

I have illustrated a tire constructed in accordance with my invention.

In the drawings, Figure 1 is a plan of the tread taken from outside the tire. Figure

2 is a section on the line, 2—2 of Figure 1 and Figure 3 is a section on the line 3—3, Figure 1.

I claim:

The ornamental design for a tire substantially as shown.

Signed by me at Baltimore, Maryland, this 25th day of June, 1923.

FRANK LAW.
